(57) **CLAIM**

We claim the ornamental design for a tire tread for a model vehicle, as shown and described.

DESCRIPTION

FIG. 1 is a top, left, front perspective view of a tire tread for a model vehicle;

FIG. 2 is front elevation view thereof;

FIG. 3 is a top plan view thereof;

FIG. 4 is a left side elevation view thereof;

FIG. 5 is a right side elevation view thereof; and,

FIG. 6 is a top, left, front perspective view of a tire tread for a model vehicle mounted on a model vehicle platform.

The broken line showing of a model vehicle platform is provided for the purposes of illustrating environmental structure and form no part of the claimed design; whereas, the broken lines depicting the interior of the tire tread for a model vehicle represent portions of the article that form no part of the claimed design.
